(57) **CLAIM**

The ornamental design for a tire as shown and described.

DESCRIPTION

FIG. 1 is a side perspective view of a first embodiment of a tire showing our new design; it being understood that the pattern is repeated throughout the circumference of the tire;

FIG. 2 is a front elevational view of the first embodiment of the tire; it being understood that the pattern is repeated throughout the circumference of the tire;

FIG. 3 is a side elevational view of the left side of the first embodiment of the tire;

FIG. 4 is a side elevational view of the right side of the first embodiment of the tire;

FIG. 5 is an enlarged fragmentary view of FIG. 2;

FIG. 6 is a sectional view of the first embodiment of the tire taken along line 6-6 of FIG. 9;

FIG. 7 is a sectional view of the first embodiment of the tire taken along line 7-7 of FIG. 9;

FIG. 8 is a sectional view of the first embodiment of the tire taken along line 8-8 of FIG. 9;

FIG. 9 is the enlarged fragmentary view shown in FIG. 5 with section lines related to FIGS. 6, 7, and 8;

FIG. 10 is a side perspective view of a second embodiment of a tire showing our new design; it being understood that the pattern is repeated throughout the circumference of the tire;

FIG. 11 is a front elevational view of the second embodiment of the tire; it being understood that the pattern is repeated throughout the circumference of the tire;

FIG. 12 is a side elevational view of the left side of the second embodiment of the tire;

FIG. 13 is a side elevational view of the right side of the second embodiment of the tire;

FIG. 14 is an enlarged fragmentary view of FIG. 11;

FIG. 15 is a sectional view of the second embodiment of the tire taken along line 15-15 of FIG. 18;

FIG. 16 is a sectional view of the second embodiment of the tire taken along line 16-16 of FIG. 18;

FIG. 17 is a sectional view of the second embodiment of the tire taken along line 17-17 of FIG. 18; and,

FIG. 18 is the enlarged fragmentary view shown in FIG. 14 with section lines related to FIGS. 15, 16, and 17.

In the drawings, the broken lines depict environmental subject matter only and form no part of the claimed design.
